UNITED STATES PATENT OFFICE.

ALBERT C. H. HOLDBROOK, OF PROVIDENCE, RHODE ISLAND.

CIGARETTE-ROLLING DEVICE.

1,379,865.

Specification of Letters Patent. Patented May 31, 1921.

Application filed May 5, 1920. Serial No. 379,167.

To all whom it may concern:

Be it known that I, ALBERT C. H. HOLDBROOK, a citizen of the United States, and resident of the city of Providence, in the 5 county of Providence and State of Rhode Island, have invented certain new and useful Improvements in Cigarette-Rolling Devices, of which the following is a specification.

This invention relates to the pocket type 10 of cigarette-rolling devices, and has for its object to provide a simple and effective device into which tobacco may be deposited and rolled into cylindrical form and a wrapper inserted therein and rolled about 15 the tobacco to form a complete cigarette, all by rotating the operating handle.

The nature and advantages of the invention will be better understood when the following detail description is taken in connection with the accompanying drawings, 20 the invention residing in the combination and arrangement of parts as claimed.

In the drawings forming part of this specification, like numerals of reference indicate similar parts in the several views and 25 wherein:—

Figure 1 is a perspective view of my improved cigarette-rolling device, showing the edge of a cigarette-wrapper extending from 30 the casing.

Fig. 2 is a central sectional end elevation illustrating the arrangement of the rolls within the casing, showing the casing in closed position causing the rolls to engage 35 a cigarette which is shown centrally located therein.

Fig. 3 shows the halves of the casing as drawn apart to permit the tobacco to be deposited between the rolls.

40 Fig. 4 is a rear end view of the casing, showing the spring member which tends to move the frame halves to open position when released.

Fig. 5 is an end view of the casing taken 45 on line 5—5 of Fig. 6, illustrating the teeth of the gears by the conventional broken lines, the centers of which gears being arranged about a circle upon the ends of the rolls, each engaging a central gear whereby 50 all are operated in unison; also showing the lock-member for retaining the frame-halves in closed position.

Fig. 6 is a longitudinal elevation with one 55 of the halves removed; showing the handle of the central gear which serves to operate

the gears on all of the other rolls surrounding it.

Fig. 7 is an enlarged longitudinal sectional view of one of the tubular rollers.

Fig. 8 shows one end of a tubular roll 60 with slots therein forming gear teeth.

Fig. 9 is an end view showing the main gear having its teeth engaging the slots in the tubular roll.

With reference to the drawings, 10 designates the frame as formed in halves, which frame is preferably constructed in cylindrical form having end portions 11 and 12. One of the frame ends is provided with an ear member 13 which serves as a 65 pivot or hinge upon which the halves are pivotally connected together. This same half is also provided with a central ear member 14 at each end. Into the ear 14 at one end is threaded a screw which binds the 70 opening yoke-shaped spring member 15 in position, the central ear 16 at the opposite end serving to receive the pivot pin 17 upon which the handle 18 turns.

The end plates 11 of these frame halves 80 are provided with bearing openings 19 arranged about in a circle for the purpose of receiving the bearing pins 20 of the rolls 21. These rolls are preferably formed in tubular shape extending longitudinally the 85 length of the tubular frame of the device and into the ends of each of which these bearing pins are forced.

The peripheries of these rolls are preferably corrugated or roughened and are 90 placed in close proximity to each other when the frame halves are in closed position.

The bearing pins 23 of the lowermost roll 22 extend through these ears 13 and serve as a pivot pin upon which the frame halves 95 swing in moving from open to closed position and vice versa.

In order to permit the frame halves to swing to open position I have left a space 24 in the bottom of the tubular frame and 100 in order to lock these frame halves in closed position I have provided a flat spring member 25 connected by a screw 26 to the end of the frame, which spring member is also provided with a protuberance or boss 27 adapted to extend into the space 24 between the frame-halves and so prevent these frame halves from opening after having been moved to closed position.

In order to release these halves to be 110

swung to open position, I have turned the free end 28 of the lock spring downwardly so that it may be readily engaged by the thumb-nail of the operator to lift its lock 5 lug 27 from the space 24, whereby the U-shaped spring 15 at the opposite end of the frame will automatically move the halves 10 to open position as illustrated in Fig. 3. On one end of each of these rolls I have provided a small pinion 29 which, as best illustrated in Fig. 5, are arranged around in a circle and each of these pinions is adapted 15 to engage a central gear 30 which is connected to the handle 18 and mounted on the pivot 17 whereby when the halves of the frame are in operative position all of the pinions engage the central gear and when the halves are swung apart as illustrated in Fig. 3, a portion only of the pinions engages 20 this central gear.

In the operation of my improved cigarette-rolling device it is only necessary to first withdraw the spring 25 from the slot 24 then the frame halves spring open under 25 action of spring 15; the tobacco is then deposited between the rolls and the halves moved to closed position, the handle 18 is then rotated causing all of the rolls to rotate in unison and roll the tobacco into cylindrical 30 shape after which the edge of the wrapper 31 is tucked down between the tobacco and the rolls when another rotation of the handle causes the wrapper to be drawn in and passed around beneath the tobacco; the 35 upper edge of the wrapper is then moistened and the rolling completed, after which the frame is again opened and the finished cigarette removed.

The operation may be repeated as often 40 as desired.

The device is very simple, compact and may be carried in the pocket of the user, and by its use a cigarette may be made very rapidly by a few turns of the operating 45 handle.

It is found in practice that in some instances instead of forming a gear 29 on a pin 20 and connecting it to the roll 21, as illustrated in Fig. 7, slots 32 may be formed 50 through the tube of the roll near the end thereof, as illustrated in Figs. 8 and 9, which slots may be engaged by the teeth 33 of the main driving gear 30.

It is found in practice by this construction that when the tobacco becomes lodged in the gear teeth of the roll it may be forced 55 through to the inside of the tube and so release the action of the gear.

By this construction the cost of providing a gear at the end of the roll may also be reduced. 60

The foregoing description is directed solely toward the construction illustrated, but I desire it to be understood that I reserve the privilege of resorting to all the 65 mechanical changes to which the device is susceptible, the invention being defined and limited only by the terms of the appended claims.

I claim:

1. A cigarette-rolling device comprising a frame, a plurality of elongated rolls arranged in a circle with their peripheries close together and having end bearings in said frame, a gear on one end of each roll, 75 and a central driving gear adapted to engage all of said gears and a handle by which the whole may be rotated in unison.

2. A cigarette-rolling device comprising a divided frame having its halves hinged together, a plurality of elongated rolls arranged in a circle having their peripheries in close proximity to each other and having bearings in said frame halves, a gear on each roll, a main central hand-operated gear for engaging the gears on all of said rolls 80 for rotating them in unison, said frame halves being adapted to be swung apart to receive the tobacco between the sets of rolls and then close, and means for locking the frame-halves in closed position. 85

3. A cigarette-rolling device comprising a frame, a plurality of tubular elongated rolls arranged in a circle with their peripheries in close proximity to each other and having end bearings in said frame, gear teeth formed on one end of each roll by providing circumferentially spaced-apart slots through the tube, a central driving gear having teeth adapted to engage the said 95 gear slots in all of said roll gears, and a handle by which said central gear and said rolls may be rotated in unison. 100

In testimony whereof I affix my signature.

ALBERT C. H. HOLDBROOK.
